US00D521342S

(12) **United States Design Patent** (10) **Patent No.:** **US D521,342 S**
Youngren (45) **Date of Patent:** **** May 23, 2006**

(54) **HAMMER**

(75) Inventor: **Robert H. Youngren**, Rockford, IL (US)

(73) Assignee: **Estwing Manufacturing Company**, Rockford, IL (US)

(**) Term: **14 Years**

(21) Appl. No.: **29/204,735**

(22) Filed: **May 3, 2004**

(51) **LOC (8) Cl.** **08-02**

(52) **U.S. Cl.** **D8/75**

(58) **Field of Classification Search** **D8/75, D8/76, 77, 78, 79, 80, 88, 89; 81/20, 21, 81/22, 23, 24, 25; 7/143, 146**

See application file for complete search history.

(57) **CLAIM**

The ornamental design for a hammer, as shown and described.

DESCRIPTION

FIG. 1 is a front perspective view of a hammer showing my new design;

FIG. 2 is a rear perspective view of the hammer;

FIG. 3 is a front elevation view of the hammer;

FIG. 4 is a rear elevation view of the hammer;

FIG. 5 is a right side elevation view of the hammer, the left side elevation being a mirror image thereof;

FIG. 6 is a top plan view of the hammer; and,

FIG. 7 is a bottom plan view of the hammer.
